UNITED STATES PATENT OFFICE.

LAMBERT N. LEGG, OF CALHOUN, GEORGIA.

CONTINUOUS KILN FOR BURNING CLAYWARE.

1,085,448.

Specification of Letters Patent.

Patented Jan. 27, 1914.

Application filed April 15, 1911. Serial No. 621,403.

To all whom it may concern:

Be it known that I, LAMBERT N. LEGG, a citizen of the United States, residing at Calhoun, in the county of Gordon and State of Georgia, have invented a new and useful 5 Continuous Kiln for Burning Clayware, of which the following is a specification.

This invention relates to an improved construction for arranging a plurality of kilns 10 in series for burning clay ware.

The primary object of the invention is to so arrange and connect the kilns that the escaping gases from the burning chambers in which the product is being fired will be 15 conducted to adjacent chambers, these gases to dry out and heat up the green material arranged in said adjacent chambers, preparatory to burning, also for the purpose 20 of conveying heat from the cooling chamber next to those under fire, to the chamber or 25 chambers under fire, to ignite the gases from the fuel being fired into said chambers.

A further object of the invention is to 30 provide a construction which will produce the greatest burning efficiency in proportion to fuel consumed, and further provide such an arrangement that will give uniform 35 burns, and at all times be under perfect control of the operator.

In the preferred embodiment of the invention, a battery of ten kilns (more or less to suit capacity desired) is employed, said 35 kilns being of the improved rectangular down draft type and being arranged side by side. The chambers or kilns which make up the battery as before stated are of the regular down draft type, (receiving heat equally from both sides) but in carrying out the invention the various chambers are connected 40 by flues, the connections being such that the waste heat from a burning chamber or chambers may be conducted to an adjacent chamber or chambers for the purpose of drying out and heating up the green material arranged within said chambers, means being also provided for conducting the waste heat from a chamber which is cooling to an adjacent chamber or chambers, in order to ignite 45 fresh fuel and promote combustion, thus reducing the amount of fuel necessary to burn the material to the minimum, the arrangement being such as to conduct the waste heat from one chamber to another for drying out the green material arranged therein 50 without going through or in any way inter- fering with chambers or kilns under fire or those being emptied or filled.

In the drawings, Figure 1 is a plan view, partly in section on the ground line, of a kiln constructed in accordance with the invention. Fig. 2 is a longitudinal vertical sectional view on a slightly enlarged scale, taken on the line 2-2 of Fig. 1. Fig. 3 illustrates a detail. Fig. 4 is a vertical longitudinal sectional view, on a slightly enlarged scale, taken on the line 4-4 of Fig. 1. Fig. 5 is a transverse vertical sectional view on the line 5-5 of Fig. 1. Fig. 6 is a detail sectional view, on an enlarged scale, taken on the line 6-6 of Fig. 1. Fig. 7 is a sectional view, on an enlarged scale on the line 7-7 of Fig. 1. Fig. 8 is a front elevation.

Referring to the figures by characters of reference, 10, 11, 12 and 13 designate certain of the compartments of the kiln, it being understood that any desired number of these compartments may be employed, the end compartments, in the present instance, being designated by the numerals 10 and 13 80 while certain of the intermediate compartments are designated by the numerals 11 and 12. Flash walls 32 are extended along opposite sides of each chamber in the kiln so as thus to form combustion chambers 33 85 provided, at their upper ends, with small openings 34 through which gases flow. These combustion chambers extend throughout the length of the flash walls and located at each end of each combustion chamber is 90 a fire box 14 provided, in the bottom thereof, with an opening 22 and in its end wall with another opening 35. A closure plate 23 is normally extended over each of the openings 22 and is adapted to be operated through the 95 lower portion of the adjacent opening 35. Thus it will be seen that communication between each fire box 14 and the opening 22 thereunder can be controlled at will.

Arranged under the floor of each compartment in the kiln is a chamber 36 in communication with the interior of the compartment thereabove through openings 37 formed in the floor of the compartment.

Extending longitudinally of the battery 105 of kilns beyond both ends of each kiln are three conduits 15, 16, and 17. The conduit 17 constitutes a suction conduit and in the particular embodiment of the invention illustrated leads to the casing of a fan con- 110

ventionally illustrated at 17^a in Fig. 3, said fan casing communicating with the two conduits 17 by a transverse conduit 17^b. Under some conditions instead of employing a fan 5 as a means for producing the desired suction through the conduit 17, the latter can be connected with a suitable stack. Each of the suction conduits 17 extends over a series of collecting flues 17' which communicate 10 with the chambers 36 under the several kiln compartments. As shown by dotted lines in Fig. 1, the vertical walls of the collecting flues 17' extend continuously from the suction flue 17 at one side of the kiln to the corresponding flue at the other side, except where they communicate with the "forwarding" flues or by-passes hereinafter referred to; but as shown in Figs. 2 and 4 such flues are not covered at points beneath the 15 greater portion of the chambers 36. Passages 17^a are formed in the tops of the outer ends of the collecting flues and are adapted to be closed by covers 17''. Access can be had to these covers 17'' through openings 20 38 formed in the top of conduit 17 directly above the covers 17'', the openings 38 being closed normally by covers 39. As there is a constant suction through the conduit 17, it will be apparent that when the closure 17'' 25 is removed from the top of the flue 17' leading to the kiln compartment through which a draft is to be created, a suction will be set up promptly through said compartment and downwardly through the floor of the compartment into the chamber 36 and thence out 30 by way of flue 17' to conduit 17.

Each collecting flue 17' has extended from it forwarding flues or by-passes 31 which communicate with the adjacent openings 22 40 of the next adjoining kiln compartment. For example, the collecting flue under the compartment 10 has two forwarding flues 31 extending therefrom and diverging so as to communicate with the openings 22 in the 45 bottom of the fire boxes of the next adjoining compartment 11. The collecting flue under the compartment 11 has diverging forwarding flues or by-passes which communicate with the openings 22 in the bottom of the fire boxes 14 of the next adjoining compartment 12. This arrangement is followed throughout the length of the battery of compartments. As clearly indicated 50 in Fig. 1 each forwarding flue or by-pass connects with two of the fire boxes of the 55 compartment under which it extends. A return flue 29 opens at one end into the chamber 36 under the end compartment 13 and at its other end into a flue 31' that communicates with the fire boxes adjacent the left 60 hand wall of the kiln compartment 10 (referring to Fig. 1) and is provided with branches 31'', similar to the forwarding flues or by-passes 31, which communicate with 65 the fire boxes adjacent the other side wall of

said compartment. This return flue 29 does not communicate with the other collecting flues 17' and forwarding flues 31.

The middle conduit 16 at each side of the kiln constitutes means for conveying gas 70 from a producer such as indicated generally at 16''. These conduits 16 are connected to the producer by end conduits 16' as shown in Fig. 1. Formed in the top of conduits 16 directly opposite each opening 35 is an 75 opening 40 adapted to be closed normally by a butterfly valve 41 which can be operated by means of a handle 42. A closure plate 43 can be located over the valve for sealing the opening 40. The innermost conduit 15 at each side of the kiln constitutes 80 a heat conducting means and each of these conduits is likewise provided, directly opposite each opening 35, with an opening 25 in the top thereof which is normally closed by 85 means of a plate 26 or the like.

Arranged above each opening 35 is a port 44. The sets of elbows 20 and 27 are adapted to be used in connection with these ports. The elbows 27 are of such length as to extend 90 from any one of the ports 44 to the nearest opening 40 while the elbows 20 are so proportioned as to extend from any one of the ports 44 to the nearest opening 25. These elbows can be manipulated by means of any 95 suitable mechanism provided for that purpose so that they can be transported readily from one port to another in the operation of the kiln. It will be understood that each kiln is provided at both ends with two doorways or openings, as indicated in Fig. 8, said 100 openings as well as the openings into the several fire boxes and combustion chambers being adapted to be closed in the ordinary manner.

The manner of using the improved kiln may be briefly described as follows: Normally, or prior to beginning to use the kiln all of the dampers 23, 17'' will be in position to close the several openings controlled 110 thereby and similarly the openings 19, 35 and 44 will be closed so that each compartment, 10 to 13 will in effect be a separate kiln. After the first chamber, 10, has been suitably filled with the ware to be burned or 115 baked and the doors through which such ware is introduced into or withdrawn from the compartment have been tightly sealed, the gas producer 16'' is started. When gas capable of burning at the openings 40, opposite the ends of the compartment 10 is obtained, the necessary tubes or elbow members 20 are positioned and connected so as to conduct gas from said openings into the fire boxes and combustion chambers of the 120 filled compartment of the kiln. The gas should be ignited before it enters the fire boxes unless the compartment has been previously heated to a red heat by suitable pre-heating means so that the gas will ignite in

the combustion chambers. After the gas has been thus ignited and a sufficient supply is available, the dampers 17" opposite the compartment 10 are opened and the draft induced through the compartment will draw the gas into the fire boxes where it will be mixed with air entering from the openings 19 and 35 and after combustion in the chambers 33 will pass into the kiln chamber 10 proper through the openings 34 being directed upwardly against the crown of such chamber and then down through the ware and out through the apertured floor into the compartment 36 and thence through flues 17' and 17 to the stack or fan casing. When the filled compartment or chamber 10 has reached a red heat the next compartment 11, should have been properly filled and ready to be heated. At this time the dampers or closure plates 23 of the fire boxes of said second chamber are removed and the dampers 17" opposite said second compartment opened. By closing the damper 17" opposite the compartment 10, it will be seen that the heat escaping from said compartment will be carried into the compartment 11 by the forwarding flues or by-passes 31.

By the time the contents of the first chamber 10 have been properly burned, the second chamber 11 should be red hot from the waste heat conducted thereto from the first compartment and by this time the third compartment of the kiln should be ready for use. The dampers 17" opposite the chamber 11 are then closed and the corresponding dampers opposite compartment 12 opened which will cause the waste heat from the compartment 11 to pass into the fire boxes of compartment 12. At this time the connection between the first compartment and the gas supply conduits should be cut off and said conduits properly connected by the elbows 20 with the fire boxes of the second compartment.

When the contents of the second compartment have been properly burned, the operations above described will be repeated so that the fourth compartment of the kiln will be receiving waste heat from the third compartment and the latter will be in direct connection with the gas supply tubes. By this time the temperature of the first compartment should have been lowered until it is about 1000°. The dampers 23 are then adjusted to close the openings controlled thereby in the fire boxes of the second compartment and the compartment 10 connected with the heat conduits 15 by the elbows 27. The seals on the doors through which the ware was introduced into the chamber 10 and through which it is to be removed from such chamber are then broken and the fifth compartment of the kiln is connected with the heat conduits 15 and the dampers 17' of said fifth compartment are opened. This

will cause a draft through the last said compartment which will draw heat from the first compartment through conduits 15 and this heat will drive off the moisture from the ware contained in the fifth compartment before the latter is heated by the waste heat from the preceding chamber, in the manner before described. Such preheating will prevent the formation of a scum upon the ware in the said fifth compartment such as is frequently caused by fumes from burning fuel coming into contact with damp material. The heat withdrawn from the first compartment and delivered into the fifth in the series does not contain any element which will dis-color the very finest of ware and also the utilization of such heat effects a decided saving in fuel. When the sixth compartment of the kiln is brought into use the temperature of the first will have been reduced so far that it may be connected to the draft flues by adjusting the dampers 17" and then the burnt ware can be removed from said first compartment and fresh ware placed therein. After six compartments have been brought into operation the operation becomes continuous. The first compartment being in communication with the draft flues to withdraw the slight amount of heat remaining therein and permit the burnt ware to be removed; the second compartment furnishing the necessary heat to water smoke or dry out the contents of the sixth compartment; the third compartment furnishing the necessary heat to ignite the gas in the fourth compartment and the waste heat from the latter acting to preheat the fifth compartment. The other chambers or compartments of the complete kiln are used to fill and empty while six thereof are being employed for burning or are in cooling condition.

Importance is attached to the fact that in the present structure, each compartment is fired at both sides so that a uniform heat is thus obtained throughout the kiln. The gas enters through the fire box and is thoroughly consumed in the combustion chamber after which the heat is carried up through the top of the combustion chambers by way of the small openings 34 and rises to the top of the kiln after which it is drawn down through the contents of the kiln and out through the bottom thereof into the forwarding and collecting flues. The hot gases, when they reach the fire boxes of the next adjoining compartment, become commingled with a fresh supply of gas which is added to raise the temperature to the desired point and, if desired, fresh air may be admitted to the fire boxes with this supply of gas so as to commingle therewith and produce practically perfect combustion. It will be noted that all of the flues and conduits used in connection with

70

this kiln are large and readily accessible for the purpose of examining and cleaning them. By providing the particular arrangement of flues disclosed, the waste heat 5 is conducted along practically straight lines from one compartment to another.

An important feature of the present construction is that all of the valves or dampers are either located outside of the kiln proper or so positioned that they can be readily manipulated and will not be affected by the heat. Also the manner in which the gas is conducted from the conduits to the kiln 10 chambers according to this invention enables the operatives to prevent waste of gas. It is only necessary to remove the connecting elbows and cover the opening in the top of the gas conduit with a flat iron plate. Any opening between the edge of the plate 15 and the surface upon which it rests can be easily closed by earth and as such openings are entirely outside the kiln there is no danger of any accident resulting from escaping gas. A further important feature 20 of the present invention is the manner in which the water smoking or drying out of moisture in advance of subjecting the contents of a chamber to high temperature is effected. By the present construction the 25 hot air is discharged into the fire boxes and thence through the combustion chambers in the same manner that the heated air is admitted instead of supplying such air indirectly and at only one point.

30 35 It is to be understood of course that the various compartments can be fired direct instead of using gas. Under these conditions, suitable fire boxes are built to suit the fuel used.

40 Having thus described the invention, what is claimed is:

1. In a continuous down draft kiln, the combination of a plurality of compartments arranged in a single row or battery and each having openings in both end walls for the introduction and removal of ware, and combustion chambers adjacent both side walls, a collection flue communicating with the bottom of each compartment and extending beyond both ends thereof, means controlled by valves outside of the walls of the kiln for establishing a uniform draft through each collection flue from both ends of the compartment thereover, and uninterrupted flues extending from each collection flue to both combustion chambers of an adjacent compartment of the kiln, for the purpose described.

2. In a continuous down draft kiln, the combination of a plurality of compartments arranged in a single row or battery and each having openings in both end walls, for the introduction and removal of ware, and combustion chambers adjacent both side walls, draft flues extending along both ends

of each compartment, a collection flue communicating with the bottom of each compartment and connecting the draft flues, valves outside of the walls of the kiln adapted to cut off each collection flue from the draft flue, forwarding flues extending from each collection flue and each adapted to communicate with both combustion chambers of an adjacent compartment, and valves in each combustion chamber, movable through openings in the end walls thereof, controlling the outlets from the forwarding flues.

3. In a continuous down draft kiln, the combination of a plurality of compartments arranged in a single row or battery and each having openings in both end walls, for the introduction and removal of ware, and combustion chambers adjacent both side walls, a collection flue communicating with the bottom of each compartment and extending beyond both ends thereof, valve controlled means for establishing a uniform draft through each collection flue from both ends of the compartment thereover, diverging forwarding flues extending from each collection flue to an adjacent compartment, each of said forwarding flues communicating with both combustion chambers in the last said compartment, and a return flue connecting the collection flue of the last compartment of the series with both of the combustion chambers of the first compartment and extending between the members of each pair of forwarding flues.

4. In a continuous kiln, the combination of a series of compartments each having combustion chambers at both sides with their discharge openings adjacent the top of the compartment, a collection flue communicating with the bottom of each compartment, valve controlled means for establishing a draft through any collection flue, two flues each connecting adjacent ends of both combustion chambers of each compartment with the collection flue of a preceding compartment in the series, and flues connecting the collection flue of the last compartment of the series with both ends of both combustion chambers of the first compartment of the series.

5. In a continuous kiln, the combination of a series of compartments each having combustion chambers at both sides provided with fire boxes having openings extending through the end walls of the compartment, draft flues at both ends of each compartment, a collection flue communicating with each compartment and connecting the draft flues, valves for cutting off the connection between each collection flue and the draft flue, flues connecting both fire boxes at each end of each compartment with the collection flue of the preceding compartment, and flues connecting the connection flue of the last

compartment of the series with all of the fire boxes of the first compartment in the series.

6. In a continuous kiln, the combination of a series of compartments each having combustion chambers at both sides provided with fire boxes having openings extending through the end walls of the compartment, draft flues at both ends of each compartment, a gas flue, a hot air flue, adjustable means for connecting any of the combustion chambers with the gas and hot air flues, a collection flue communicating with each compartment and connecting the draft flues, valves for cutting off the connection between each collection flue and the draft flue, flues connecting both fire boxes at each end of each compartment with the collection flue of the preceding compartment, and flues connecting the collection flue of the last compartment of the series with all of the fire boxes of the first compartment in the series.

7. In a continuous kiln, the combination of a series of compartments each having combustion chambers at both sides provided at their ends with fire boxes communicating with openings through the end walls of the compartment, a collection flue communicating with the bottom of each compartment, valve controlled means for establishing draft through any of the collection flues, a pair of forwarding flues extending from the collection flue of each of the compartments except the last of the series beneath the next compartment of the series, each of said pair of forwarding flues communicating with a fire box in both of the combustion chambers of the compartment beneath which it extends, flues connecting the collection flue of the last compartment of the series with all of the fire boxes of the first compartment of the series, and closures operable through the openings in the end walls of each compartment for cutting off communication between the forwarding flues and the fire boxes.

8. A continuous kiln including a longitudinal series of compartments, combustion chambers along opposite sides of each compartment, there being a fire box at each end of each combustion chamber, said chambers extending upwardly toward the top of the compartment, each fire box having an opening in the bottom thereof, slideable closures normally bridging the openings, there being openings in the end walls of the fire boxes through which said closures are shiftable and through which air is admitted to the fire boxes, a collection flue under each compartment and communicating with the bottom thereof, a draft flue, means for controlling communication between the collection flues and the draft flue, and flues for conveying gases from the collection flues to the fire boxes of the next adjoining compartments.

9. A continuous kiln including a longitudinal series of compartments, fire boxes at opposite sides of each compartment, there being an opening in the bottom of each fire box and another opening in the end wall of each fire box, a slideable closure operable through said end opening for controlling communication between the fire box and the bottom opening therein, said end opening also constituting an air inlet, a collecting flue extending under each compartment, a draft flue, separate means for placing the respective collecting flues in and out of communication with the draft flue, and a forwarding flue extending from the collection flue under each compartment to the openings in the bottoms of the fire boxes of the next following compartment of the continuous kiln.

10. In a continuous kiln, a longitudinal series of compartments, fire boxes at opposite sides of each compartment, there being an opening in the bottom of each fire box and an end opening in each fire box, a closure for the bottom opening and operable through the end opening, said end opening also constituting an air inlet, a collecting flue under each compartment, a suction conduit, separate means for placing the respective collecting flues out of communication with the suction conduit, means for conveying gases from the collection flues to the openings in the bottoms of the fire boxes of the next adjoining compartments, and means for conveying the gases from the last compartment of the series to the first compartment, including a return flue.

11. A continuous kiln including a longitudinal series of compartments, fire boxes at opposite sides of each compartment and having openings in the bottoms thereof, and an air inlet opening in one end, a slideable closure operable through the air inlet opening for closing communication between the fire box and the bottom openings, each fire box having an inlet port, a collecting flue under each compartment, a suction conduit, means for closing communication between said conduit and the respective collecting flues, means for conveying hot gases from the collecting flue of each compartment to the openings in the bottoms of the fire boxes of the next following compartment of the continuous kiln, a gas conduit, and means for placing said conduit in communication with any one of the ports.

12. A continuous kiln including a longitudinal series of compartments, fire boxes at opposite sides of each compartment and having openings in the bottoms thereof, and an air inlet opening in one end, a slideable closure operable through the air inlet opening for closing communication between the fire box and the bottom openings, each fire box having an inlet port, a collecting flue

8
under each compartment, a suction conduit, means for closing communication between said conduit and the respective collecting flues, means for conveying hot gases from the collecting flue of each compartment to the openings in the bottoms of the fire boxes of the next following compartment of the continuous kiln, a gas conduit, means for placing said conduit in communication with any one of the ports, a heat conducting con-

duit, and means for placing said conduit in communication with the ports of any of the fire boxes.

In testimony that I claim the foregoing as my own, I have hereto affixed my signature in the presence of two witnesses.
